UNITED STATES PATENT OFFICE

94,865

DESIGN FOR A SHOE

Oliver J. Sullivan, Hudson, Mass., assignor to Corbin-Holmes Shoe Co., Hudson, Mass., a corporation of Massachusetts

Application January 17, 1935, Serial No. 54,890

Term of patent 3½ years

To all whom it may concern:

Be it known that I, Oliver J. Sullivan, a citizen of the United States, residing at Hudson, in the county of Middlesex and Commonwealth of Massachusetts, have invented a new, original, and ornamental Design for a Shoe, of which the following is a specification, reference being had to the accompanying drawing, forming a part thereof, in which the figure is a view in side elevation of a shoe showing my new design, the sole, heel and counter portions being conventional and shown in dotted lines. Both sides of the shoe are substantially the same in appearance.

I claim:

The ornamental design for a shoe substantially as shown and described.

In testimony whereof, I have affixed my signature hereto.

OLIVER J. SULLIVAN.
